UNITED STATES PATENT OFFICE.

ALBERT A. FREVERT, OF ALMA, MICHIGAN, ASSIGNOR TO CRIPPEN MANUFACTURING COMPANY, OF ALMA, MICHIGAN, A CORPORATION OF MICHIGAN.

VIBRATING MECHANISM.

Application filed August 23, 1926. Serial No. 131,029.

This invention relates to vibratory mechanism and the like, and especially to a mechanism for vibrating a resiliently mounted shoe in which screens are secured for screening beans and seeds of various kinds.

The prime object of the invention is to design a vibrating mechanism which will remain in neutral non-vibrating position until the speed of the pulley or driven member has reached a certain R. P. M., and which will then automatically and sharply shift to vibratory position where it is held by centrifugal force.

Another object is to provide a vibratory mechanism of simple and substantial design, which is adjustable as to length of vibration, and also adjustable as to the speed at which the vibrator will shift to vibratory position.

A further object is to design a vibrator, and provide resilient means for opposing the shifting of the counterbalanced counterweight into vibratory position until the speed of the machine has reached a certain R. P. M., acting in a like manner to sharply shift the counterweight back to non-vibrating position, when the speed of the machine has slowed to a certain R. P. M.

The above and other objects will appear as the specification progresses, reference being had to the accompanying drawing in which I have shown the preferred embodiment of my invention, and in which like reference numerals indicate like parts throughout the several views thereof.

In the drawing:

Fig. 1 is a side view of a pulley showing my vibrating mechanism secured thereto and in non-vibrating position.

Fig. 2 is also a side view showing the mechanism shifted to vibratory position.

Fig. 3 is a vertical sectional view through the pulley and counterbalanced counterweight.

In vibratory mechanism in general, and particularly vibratory mechanism based on the counterbalanced idea, the counterweight chuck's back and forth into and out of vibratory position as soon as the machine is started, and continues to do so until the machine has attained sufficient speed so that the centrifugal force will hold it in vibratory position.

The vibrations produced between the time of starting, and the time the machine or

pulley is rotating at proper speed are undesirable, producing a very poor screening effect, and this undesirable feature I have overcome by designing a vibrating mechanism which does not operate until a certain predetermined speed has been attained, and which acts in a like manner when the power is cut off.

Referring now particularly to the drawing in which I have shown the preferred embodiment of my invention, the numeral 5 indicates a cylindrical pulley which is provided with a hub 6, and a rim 7, one side being closed by a web 8, which can be suitably cored as shown at 8^a, or the pulley can be cast with spokes (not shown) in the usual manner, the hub being bored as shown at 9 to receive the shaft on which the pulley is mounted.

The vibrating mechanism comprises a counterbalanced counterweight 10 formed with a centrally disposed opening 11 embracing the hub of the pulley, the end 12 being enlarged, the outer rim or edge being turned to approximately the same diameter as the inner rim of the pulley, a leg 13 being cast integral with the counterweight, and is provided with an opening in the outer end thereof for reception of a bolt 14, and by means of which it is pivotally secured to the pulley.

The opposite side of this counterweight is bored as shown at 15 and a compression spring 16 is mounted therein, one end engaging the hub of the pulley. This spring opposes the shifting of said counterweight until the speed has reached a certain R. P. M. as will be presently described.

The adjusting means for adjusting the throw or vibration comprises a threaded opening 17 provided in the enlarged end of the counterweight, and an adjusting bolt 18 is threaded therein, the one end engaging the inner surface of the pulley rim when the mechanism is in vibratory position and limits the outward movement of the counterweight, and it will be obvious that the length of throw or vibration can be easily regulated by manipulation of the bolt.

The adjusting means to determine the R. P. M. at which the counterbalanced counterweight shall shift to vibratory position, is a similar arrangement, a threaded opening 19 being provided in the opposite side and an adjusting bolt 20 is threaded

therein, a lock nut 21 being provided on the bolt as shown for locking it in position, the head 20^a of said bolt contacting with the rim of the pulley when the mechanism is in non-vibrating position, and serves to hold the counterweight slightly off center and against the pressure of the spring, and adjustment thereof serves (when the machine is operating) to regulate the speed at which the counterweight will shift to vibrating position, consequently, it will be clear that the device can be so regulated that there will be no vibration of the shoe which supports the screens, until the proper predetermined pulley velocity is attained, and the screening action will be at the highest point of efficiency at all times.

In practise the counterweight is set slightly off center, the length of throw or vibration being regulated by the adjusting bolt 18, power is applied to the machine, the vibrating mechanism remaining in non-vibrating position until a certain speed is attained, the distance which the counterweight is off center being compensated for by the weight of the shoe or other mechanism which is being vibrated, until overcome by centrifugal force, when the mechanism automatically shifts to vibrating position.

From the foregoing description it will be obvious that I have perfected a very simple, economical and effective adjustable vibrating mechanism for screening devices and the like.

What I claim is:—

1. A vibrating mechanism comprising a cylindrical member having a hub, a counterbalanced counterweight pivotally secured thereto and having a centrally disposed opening embracing said hub, resilient means interposed between the counterweight and hub and adjustable means for adjusting the offcenter movement of the counterweight.

2. A vibrating mechanism comprising a cylindrical member provided with a hub, of a counterbalanced counterweight pivotally secured thereto and having a centrally disposed opening embracing said hub, resilient means mounted in the counterweight and engaging said hub, and means for adjusting the position of the counterweight with relation thereto.

3. A vibrating mechanism comprising a driven cylindrical member provided with a hub, of a counterbalanced counterweight

pivotally secured thereto and having a centrally disposed opening embracing said hub, means for adjusting said counterweight with relation to the hub, and resilient means mounted in said counterweight and engaging said hub to oppose the shifting of said counterweight until a certain predetermined speed has been reached.

4. A vibrating mechanism comprising a cylindrical driven member provided with a hub, of a counterbalanced counterweight pivotally secured thereto and near the outer rim thereof and having a centrally disposed opening embracing the hub, resilient means mounted in the hub, means for determining the R. P. M. at which said mechanism will move to vibrating position, and adjustable means for regulating the length of throw or vibration.

5. A vibrating mechanism comprising a driven member provided with a hub, a counterbalanced counterweight pivotally secured thereto and formed with a centrally disposed opening embracing the hub, adjustable means for adjusting the throw or vibration of said counterweight, and adjustable means for adjusting the offcenter non-vibrating position thereof, and a spring mounted in the counterweight and engaging the hub for opposing the shifting of said counterweight until a certain predetermined speed has been reached.

6. A vibrating mechanism comprising a driven member, a counterbalanced counterweight secured thereto, adjustable means for adjusting the throw of said counterweight, adjustable means for adjusting the offcenter non-vibrating position thereon and resilient means mounted in said counterweight and engaging said driven member.

7. A vibrating mechanism comprising a driven member, a counterbalanced counterweight secured thereto, adjustable means for adjusting the throw of said counterweight, adjustable means for adjusting the non-vibrating position thereof, and resilient means interposed between the driven member and the counterweight for opposing the shifting of said counterweight until the driven member has reached a certain predetermined speed.

In testimony whereof I affix my signature.

ALBERT A. FREVERT.
